Primary Examiner — Darcey E Gottschalk(74) *Attorney, Agent, or Firm* — LAPPL UEBELL IP LAW, LLP; Franklin D. Ubell(57) **CLAIM**

The ornamental design for a combined pump top and skirt, as shown and described.

DESCRIPTION

FIG. 1 is a front perspective view of the combined pump top and skirt;

FIG. 2 is a front view thereof;

FIG. 3 is back view thereof;

FIG. 4 is a left side view thereof;

FIG. 5 is a right side view thereof;

FIG. 6 is a top view thereof; and,

FIG. 7 is a bottom view thereof.

In the drawings, the broken lines show a related liquid storing component that forms no part of the claim.
